UNITED STATES PATENT OFFICE.

HERMAN C. MAISE, OF DETROIT, MICHIGAN, ASSIGNOR TO BRIGGS MANUFACTURING COMPANY, OF DETROIT, MICHIGAN, A CORPORATION OF MICHIGAN.

LOCK BOARD.

Application filed November 5, 1923. Serial No. 673,011.

This invention relates to doors and refers more particularly to means for supporting the locks and window control mechanisms thereof.

5 An object of the invention is to provide a single member for supporting all of the window control mechanism as well as the lock of a door.

Another object is to provide a support 10 that is adapted to fit within depressed portions of a door frame so that the outer surface of the support will be flush with the adjacent faces of the frame to provide an even surface for the usual trimming material for the door.

Another object is to provide simple and effective means for positioning the support upon the frame of the door when applied thereto.

20 With the above and other objects in view, the invention consists in certain novel features of construction, combination, and arrangement of parts as will be more fully described and particularly pointed out in 25 the appended claims.

In the accompanying drawing:—

Figure 1 is an inside elevation partly broken away of a motor vehicle door with the construction embodying my invention 30 applied thereto;

Figure 2 is a sectional view taken on the line 2—2 of Figure 1;

Figure 3 is a sectional view taken on line 3—3 of Figure 1;

35 Figure 4 is a sectional view taken on line 4—4 of Figure 1;

Figure 5 is a sectional view taken on the line 5—5 of Figure 1.

In the manufacture of doors for vehicle 40 bodies it is usual to connect the uprights of a door frame by a board that supports a suitable lock for the door as well as a part of the window control mechanism and to provide a gusset plate that is secured to one of the uprights and that supports the other parts of the control mechanism. However, with such constructions it frequently happens that either the lock boards or the gusset plates or both are made incorrectly or 45 are secured inaccurately to the door frame so that as a result the parts of the control mechanism can not be assembled properly for operation.

With the present invention these objectionable features are overcome entirely and

I preferably provide a single board that is constructed to support all of the window control mechanism as well as the lock for the door.

Referring now to the drawing in which like characters of reference designate corresponding parts throughout the several views, the numeral 1 designates a window that is adapted to be raised or lowered in a door 2, preferably of a vehicle body. In the upper portion of the door is an opening 3 that is adapted to be closed by the window when in raised position, while in the lower portion of the door is a vertical pocket 4 that communicates with the opening 3 and that is adapted to receive the window when in lowered position. This window is preferably a sashless glass panel that is adapted to slide in suitable guideways 5 secured to the upright members 6 of the door frame and 75 is adapted to be raised or lowered by suitable control mechanism designated generally by the numeral 7.

For reinforcing the door intermediate its ends, I preferably provide a channel-shaped 80 board 8 that is secured to the upright members 6 of the frame adjacent to a suitable belt finish strip 9. This board preferably supports a suitable lock 10 for the door, and for this purpose, is preferably provided at 85 one end with an opening 15 that receives the working parts of the lock. The board 8 is also provided with a depressed portion 12 that extends upwardly from the upper edge of the opening 15 for receiving the operating handle (not shown) of the lock. The lock casing 14 may be any suitable design 90 and is preferably detachably secured to the outer side of the lock board.

For supporting all of the window control 95 mechanism, as well as the lock for the door, the board 8 is preferably provided at its lower edge with a downward extension 16 upon which the lower end of a window actuating lever 7 of the control mechanism 100 is pivotally mounted. For actuating this lever there is a screw 18 that threadedly engages a bearing 19 mounted on the lever 7 adjacent to the lower end thereof and that meshes with suitable gearing 20 in a 105 gear case 21 secured in an opening 22 in the lock board 8 adjacent to the extension 16. A counter-balancing coil spring 23 is terminally secured to the inturned flange 24 at the upper edge of the lock board and 110

to the lever 7 adjacent the bearing 19, while a suitable crank 25 extending into the gear casing is used to operate the gearing for rotating the screw 18 to actuate the lever 7 against the tension of the spring 23.

In order that an even surface may be provided for the usual trimming material 27 for the door, the upright members 6 are preferably provided with depressed portions 28 that receive the end portions of the lock board 8 so that the outer surface of the board will be flush with the adjacent face of the upright members. To insure a rigid connection between the lock board and the uprights, the end portions of the board are preferably welded along the upper and lower edges thereof to the upper and lower edges of the depressed portions 28. For positioning the lock board properly in the depressions 28 when applied to the door frame, the board is preferably provided at each end with spaced inturned flanges 29 that engage the opposed faces of the uprights. Thus, the flanges 29 prevent endwise movement of the board while the depressed portions 28 hold the board against vertical movement.

It will also be noted that the upper and lower flanges 24 and 30 respectively of the board are cut away at their ends so that they will also abut the opposed faces of the upright members 6 of the frame and thus will cooperate with the flanges 29 to position the board upon the uprights.

The extension 16 is preferably provided at its lower end with a horizontal flange 33 that extends inwardly and has a vertical portion 34 that extends downwardly in substantially parallel relation to the extension 16, the flange 33 and the portion 34 being formed, in the illustrated construction, of

metal struck out from extension 16. The pivot pin 32 for the lever 7 extends through aligned openings in the extension 16 and vertical portion 34 of the flange 33. Thus, the flange 33 serves as a support for the lever 7 in addition to serving as a positioning member for the board.

What I claim as my invention is:

1. The combination with a frame, and a closure movable in said frame, of a pivotal lever, an actuating connection from said lever to said closure, and a sheet metal support for said lever formed with an integral projection, having its end portion bent in parallelism with said support, and a shaft extending between said bent end portion and the end of said support pivotally mounting said lever.

2. The combination with a frame and a window movable in said frame, of a sheet metal member secured to said frame, a lock carried by said member at one end thereof, said member being provided at its other end with a portion extending downwardly therefrom and provided with an integral struck out portion, a lever having one end thereof connected to said window and the other end supported between said sheet metal member and the struck out portion thereof.

3. The combination with a door frame having spaced uprights, of a sheet metal lock and window lifter supporting member connecting said uprights, and provided adjacent to its opposite ends with lateral projections that engage the uprights, one of said projections being substantially U-shaped and constituting a pivot bearing for a part of said window lifter.

In testimony whereof I affix my signature.

HERMAN C. MAISE.
